UNITED STATES PATENT OFFICE

114,849

DESIGN FOR A DENTAL UNIT

Edward L. Monnot, Canton, Ohio, assignor to The Weber Dental Manufacturing Company, Canton, Ohio, a corporation of Ohio

Application August 6, 1938, Serial No. 79,163

Term of patent 7 years

To all whom it may concern:

Be it known that I, Edward L. Monnot, a citizen of the United States, residing at Canton, in the county of Stark and State of Ohio, have invented a new, original, and ornamental Design for a Dental Unit, of which the following is a specification, reference being had to the accompanying drawing, forming part thereof.

unit showing my new design, the dominant features of the design being shown in full lines; and

Fig. 2, a transverse sectional view on a slightly enlarged scale substantially on the line 2—2, of Fig. 1, showing the contour of the standard.

I claim:

The ornamental design for a dental unit, as shown and described.

EDWARD L. MONNOT.
